EXPANSION CORE

Filed Sept. 14, 1923

UNITED STATES PATENT OFFICE.

JOHN R. TAYLOR AND ERVIN WOOD, OF SAWTELLE, CALIFORNIA.

EXPANSION CORE.

Application filed September 14, 1923. Serial No. 662,736.

This invention relates to expansion cores and more particularly to a core designed for use in rolls of print paper such as used in newspaper printing.

5 It is the present practice, in rolling print paper, to roll it upon the core which is shipped with the paper and when the paper is used from the core the latter is then returned to the paper company from whom 10 the paper was purchased thus causing not only the expense of shipping the cores but also the expense of a man to take care of the cores as well as the necessity of keeping a relatively large stock of cores upon hand.

15 It is an object of this invention to provide an expansion core particularly designed for use in rolls of print paper, which may be contracted to permit its removal from the roll of paper, after the roll has 20 been completed, and which may be contracted for insertion into a roll of paper, at the printing press after which it may be expanded to properly fit the interior of the roll thereby requiring only two cores, one 25 at the paper mills and one at the printing establishment for properly taking care of the roll and will consequently eliminate the expense contingent on the use of cores as above referred to.

30 Other objects of the invention will appear in the following detailed description taken in connection with the accompanying drawings wherein:

Fig. 1 is a longitudinal section through 35 the improved expansion core.

Fig. 2 is a cross section through the core taken on the line 2—2 of Fig. 1.

Fig. 3 is a cross section taken on the line 3—3 of Fig. 1.

40 Fig. 4 is a cross section taken on the line 4—4 of Fig. 1.

Fig. 5 is a detail section taken on the line 5—5 of Fig. 1.

45 Referring more particularly to the drawings, the improved expansion core comprises a central shaft 1, which is rectangular in cross section throughout the major portion of its length and has its ends 2 and 3 rounded, in cross section to provide trunnions or bearing shafts for the core. The rectangular shaft 1 has a plurality of blocks 4 attached thereto at spaced points, in any suitable manner such as by set screws 5. The blocks 4 are arranged in pairs which have 50 their facing ends inclined in parallel relation as shown at 6. The inclined parallel

ends 6 fit against the inclined ends of blocks 7 which are attached to the housing strips 8 of the core by screws or analogous means as shown at 9. The strips 8, a plurality of 60 which are provided, have their facing edges spaced, so as to permit movement of these strips towards or from the shaft 1 for increasing the diameter of the core to permit the core to be expanded to properly fit 65 the interior of a roll of print paper or the like, it being understood that the strips 8 may be moved inwardly towards the shafts to permit the core to be contracted or its diameter reduced for placing it into the 70 center opening in the roll of print paper. The shaft 1 has a portion of its length intermediate the end 3 and the adjacent end of its rectangular portion screw threaded as shown at 10, and a nut 11 is threadedly 75 mounted thereon. The nut 11 has an annular flange 12 formed at one end thereof which is engaged by the annular channel 13 formed on the end cap 14. The end cap 14 is preferably made in two sections which 80 are clamped together as shown at 15 in Fig. 4 of the drawings.

Radial pins 16 are carried by the end cap 14 and engage through suitable openings 17 formed in the strips 8 for connecting these 85 strips with the end cap 14 to permit the strips to be moved longitudinally of the shaft 1 by adjustment of the nut 11 along the threaded portion 10. The longitudinal movement of the strips 8, will either move 90 the strips inwardly towards the shaft or outwardly from the shaft 1 depending upon the direction in which they are moved owing to the slidable engagement between the inclined engaging surfaces of the blocks 4 95 and 7. Suitable guides 18 are carried by the shaft 1 for engaging the side edges of the blocks 7 and guiding their relative movement. The blocks 4 are pinned by means of suitable pins 19 to the guides 18.

An end cap 20 is detachably mounted upon the end of the shaft 1 remote from the cap 14 and it is held in place by a set screw 21.

It is, of course, to be understood that the 105 invention may be constructed in other manners and the parts associated in different relations and, therefore, we do not desire to be limited in any manner except as set forth in the claim hereunto appended.

Having thus described our invention what we claim is:

An expansion core comprising a central shaft of rectangular cross-section having longitudinal guides on its sides, an outer shell composed of a plurality of individual strips, a flanged end cap, inwardly directed pins on the flange of the end cap connecting said end cap to said strips for connecting the strips for unitary movement, a nut threaded upon said shaft and connected to said end cap for moving the strips longitudinally upon adjustment of the nut, blocks carried by said shaft between said longitudinal guides and arranged in pairs having their facing

ends inclined, and blocks carried by said strips and disposed between said longitudinal guides and having inclined ends slidably engaging the inclined ends of said first named blocks whereby said strips will be moved inwardly towards or outwardly from the shaft upon longitudinal movement of the strips. 15 20

In testimony whereof we affix our signatures.

JOHN R. TAYLOR.
ERVIN WOOD.
